(57) CLAIM

The ornamental design for a brassiere, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a brassiere in an unworn configuration.

FIG. 2 is a rear view thereof.

FIG. 3 is a perspective view thereof; and,

FIG. 4 is a front view thereof, shown in a worn configuration.

The broken lines superimposed over the color drawings illustrate portions of the brassiere that form no part of the claimed design.

1 Claim, 4 Drawing Sheets
(4 of 4 Drawing Sheet(s) Filed in Color)

FIG. 1

FIG. 2

FIG. 4
